CLAIM

The ornamental design for a surgical tray, as shown and described.

DESCRIPTION

FIG. 1 is a top, front, right perspective view of a surgical tray according to the present disclosure.

FIG. 2 is a top view of the surgical tray of FIG. 1.

FIG. 3 is a bottom view of the surgical tray of FIG. 1.

FIG. 4 is a front view of the surgical tray of FIG. 1.

FIG. 5 is a right side view of the surgical tray of FIG. 1; and, FIG. 6 is a left side view of the surgical tray of FIG. 1.

The broken lines in the Figures depict portions of the surgical tray that form no part of the claimed design.
